United States Patent Office.

CHARLES G. BOYER, OF GREENFIELD, INDIANA.

Letters Patent No. 66,292, dated July 2, 1867.

HAY-RACK.

The Schedule referred to in these Letters Patent and making part of the same.

TO ALL WHOM IT MAY CONCERN:

Be it known that I, CHARLES G. BOYER, of Greenfield, in the county of Hancock, and in the State of Indiana, have invented certain new and useful improvements in Hay-Racks; and do hereby declare that the following is a full, clear, and exact description thereof, reference being had to the accompanying drawings, and to the letters of reference marked thereon, making a part of this specification.

My invention consists in constructing a hay-rack in such a manner as it can be taken apart or put together without much trouble, and stored away when not in use.

In the annexed drawings, A A represent the two horizontal beams connected together by the cross-pieces B B to form the bottom of the rack, which is to be placed upon the wagon. The bottom of the beams A A have suitable notches, into which are placed the cross-pieces B' connected to the pieces B. Near each end are two pivoted arms a a, which are also pivoted to the upright braces D, that form the supports for the top rails A'. It will be observed that the cross B' extends slightly beyond the beams A, so that the lower ends of the braces D are rested (see 2, fig. 2,) thereon, and lean against the outside of beams A. The tops of the braces are dove-tailed, and fit into dove-tailed grooves in the top rails A', so that they can be readily taken off from the braces by merely slipping out of their grooves. At each of the top cross-pieces E E there is a small loop into which is caught a hook over a metallic plate, which is hinged to the end braces D for securing the end of the rack. C represents the ladder which is attached to the bottom cross-piece B', by means of small hooks on its ends and loops placed upon the cross-piece. The upper piece E has an opening cut in its inner face through which the ladder passes, where it is secured in a vertical manner by a metal plate, loop, and hook c', similar to the plate, loop, and hooks c on the braces. At the rear end of the rack is an upright beam secured to the wagon-rack in a manner similar to the ladder C. This pole is intended to be used in lieu of the chain or rope which connects the beam-pole to the rack. In this hay-rack there are no nails or screws excepting those (x) used in connecting the arms a a to the cross-pieces B' and braces D, so when not in use the entire rack can be taken to pieces and folded up for storing away. By slipping off the rails A' from the braces the braces can be raised, and the arms a a with cross-pieces B' folded and extracted from the bottom of the rack.

Having thus fully described my invention, what I claim as new, and desire to secure by Letters Patent, is—

A hay-rack with top rails A' dove-tailed to the standards D, and ends connected by the plates and hooks c c, in combination with the pivoted arms a a, and cross-pieces B', for forming a portable rack provided with upright beams at one end and ladder at the other, substantially as set forth.

In testimony that I claim the foregoing I have hereunto set my hand and seal this 20th day of April, 1867.
